The ornamental design for a modular packing set components, as shown and described.

DESCRIPTION

FIG. 1 is a plan view of a modular packing set components showing the back portion of the design with each of the various embodiments of the front portion of our new design; FIG. 2 is a perspective view of the back portion of the modular packing set components, as shown in FIG. 1; FIG. 3 is a left side elevational view of the back portion of the modular packing set components, as shown in FIG. 1; FIG. 4 is a front plan view of the back portion of the modular packing set components, as shown in FIG. 1; FIG. 5 is a right side elevational view of the back portion of the modular packing set components, as shown in FIG. 1; FIG. 6 is a top elevational view of the back portion of the modular packing set components, as shown in FIG. 1; FIG. 7 is a bottom elevational view of the back portion of the modular packing set components, as shown in FIG. 1; FIG. 8 is a back plan view of the back portion of the modular packing set components, as shown in FIG. 1; FIG. 9 is a perspective view of a first embodiment of the front portion of the modular packing set components, as shown in FIG. 1; FIG. 10 is a left side elevational view of the front portion of the modular packing set components, as shown in FIG. 9; FIG. 11 is a front plan view of the front portion of the modular packing set components, as shown in FIG. 9; FIG. 12 is a right side elevational view of the front portion of the modular packing set components, as shown in FIG. 9; FIG. 13 is a top elevational view of the front portion of the modular packing set components, as shown in FIG. 9; FIG. 14 is a bottom elevational view of the front portion of the modular packing set components, as shown in FIG. 9; FIG. 15 is a back plan view of the front portion of the modular packing set components, as shown in FIG. 9; FIG. 16 is a perspective view of a second embodiment of the front portion of the modular packing set components, as shown in FIG. 1; FIG. 17 is a left side elevational view of the front portion of the modular packing set components, as shown in FIG. 16; FIG. 18 is a front plan view of the front portion of the modular packing set components, as shown in FIG. 16; FIG. 19 is a right side elevational view of the front portion of the modular packing set components, as shown in FIG. 16; FIG. 20 is a top elevational view of the front portion of the modular packing set components, as shown in FIG. 16; FIG. 21 is a bottom elevational view of the front portion of the modular packing set components, as shown in FIG. 16; FIG. 22 is a back plan view of the front portion of the modular packing set components, as shown in FIG. 16; FIG. 23 is a perspective view of a third embodiment of the front portion of the modular packing set components, as shown in FIG. 1; FIG. 24 is a left side elevational view of the front portion of the modular packing set components, as shown in FIG. 23; FIG. 25 is a front plan view of the front portion of the modular packing set components, as shown in FIG. 23; FIG. 26 is a right side elevational view of the front portion of the modular packing set components, as shown in FIG. 23;

FIG. 27 is a top elevational view of the front portion of the modular packing set components, as shown in FIG. 23; FIG. 28 is a bottom elevational view of the front portion of the modular packing set components, as shown in FIG. 23; FIG. 29 is a back plan view of the front portion of the modular packing set components, as shown in FIG. 23; FIG. 30 is a perspective view of a fourth embodiment of the front portion of the modular packing set components, as shown in FIG. 1; FIG. 31 is a left side elevational view of the front portion of the modular packing set components, as shown in FIG. 30; FIG. 32 is a front plan view of the front portion of the modular packing set components, as shown in FIG. 30; FIG. 33 is a right side elevational view of the front portion of the modular packing set components, as shown in FIG. 30; FIG. 34 is a top elevational view of the front portion of the modular packing set components, as shown in FIG. 30; FIG. 35 is a bottom elevational view of the front portion of the modular packing set components, as shown in FIG. 30; FIG. 36 is a back plan view of the front portion of the modular packing set components, as shown in FIG. 30; FIG. 37 is a perspective view of a fifth embodiment of the front portion of the modular packing set components, as shown in FIG. 1; FIG. 38 is a left side elevational view of the front portion of the modular packing set components, as shown in FIG. 37; FIG. 39 is a front plan view of the front portion of the modular packing set components, as shown in FIG. 37; FIG. 40 is a right side elevational view of the front portion of the modular packing set components, as shown in FIG. 37; FIG. 41 is a top elevational view of the front portion of the modular packing set components, as shown in FIG. 37; FIG. 42 is a bottom elevational view of the front portion of the modular packing set components, as shown in FIG. 37; FIG. 43 is a back plan view of the front portion of the modular packing set components, as shown in FIG. 37; FIG. 44 is a perspective view of a sixth embodiment of the front portion of the modular packing set components, as shown in FIG. 1; FIG. 45 is a left side elevational view of the front portion of the modular packing set components, as shown in FIG. 44; FIG. 46 is a front plan view of the front portion of the modular packing set components, as shown in FIG. 44; FIG. 47 is a right side elevational view of the front portion of the modular packing set components, as shown in FIG. 44; FIG. 48 is a top elevational view of the front portion of the modular packing set components, as shown in FIG. 44; FIG. 49 is a bottom elevational view of the front portion of the modular packing set components, as shown in FIG. 44; and, FIG. 50 is a back plan view of the front portion of the modular packing set components, as shown in FIG. 44. The broken lines shown in the figures are for purposes of illustrating environmental structure and portions of the modular packing set components that form no part of the claimed design.
